ELECTRICAL CALCULATING MACHINE

Hans P. Luhn, Armonk, N. Y., assignor to International Business Machines Corporation, New York, N. Y., a corporation of New York

Application August 28, 1943, Serial No. 500,325

6 Claims. (Cl. 235—61)

The present invention relates to accounting machines and more particularly to the data accumulating mechanism thereof.

The principal object of the present invention is to provide a novel accumulator of the electrical relay type, in which the arrangement of relay magnets and contacts is considerably improved and simplified over prior devices.

Another object of the invention is to provide a relay accumulator in which all denominational orders are of like construction and arrangement, and in which the orders are connectable in series to provide an accumulator of any desired denominational capacity.

A further object is to provide novel carry determining mechanism for a relay accumulator operable for both adding and subtracting operations.

In carrying out the objects of the invention, there is provided in each order a set of two-position relay magnets and associated contacts and a set of contacts settable to represent an amount to be entered, and for each order there are provided two so-called adding chain sets of connections. Through one chain the relays are operated in accordance with the algebraic sum of two amounts without carries, and through the other chain the relays are operated in accordance with the algebraic sum of two amounts with carries. The setting of parts of both sets of contacts determines what chain is to be effective by connecting the appropriate chain of each order to the source of current from which a single impulse passing through all orders will operate the relays in accordance with the algebraic sum of the two amounts.

A novel arrangement is provided whereby the highest order determining means selects the adding chain of the lowest order, whereby when subtracting operations are performed in accordance with the method of complementary addition the so-called elusive one is applied to the lowest order, whenever the highest order passes through zero.

A further object is to provide a novel indicating means for displaying at all times the true value of the amount entered into the relay accumulator together with its algebraic sign.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a detail showing the construction of the amount entering keys.

Fig. 2 is a detail of one of the accumulating relay magnets in its unset position.

Fig. 3 is a detail of one of the accumulating relay magnets in its set position.

Fig. 4 is a diagram showing certain circuits in simplified form.

Fig. 5 is a view showing the elements included in one denominational order of the accumulating mechanism.

Fig. 6 is a diagram showing how four denominational orders of an accumulator are arranged by repeating the elements in Fig. 4 and interconnecting them as indicated.

Fig. 7 is a partial diagram of a modified circuit arrangement.

In carrying out the objects of the invention, each denominational order of the accumulating mechanism comprises four so-called accumulating relay devices, each of which has a value assigned thereto in accordance with the first four terms of the binary progression, namely, 1, 2, 4 and 8. The relays each have a "set" and an "unset" position with an entry in any one thereof being represented by its "set" condition. Accordingly, any of the digits from 0 to 9 can be represented by the setting of one or more of the relays.

For each denominational order there is provided a set of four so-called entering relays which also have the values of the binary progression assigned thereto. These latter relays are energized in combinational manner to represent a digit to be entered and for each order such digit may also be from 0 to 9.

In the operation of the devices, with the accumulating relays of a denominational order set to represent a digit, another digit to be entered is set on the entering relays. Both kinds of relays consequently effect the adjustment of a system of contacts or switches, so electrically interconnected that a continuous circuit is established which causes the accumulating relays to assume a setting representing the units digit of the sum or difference of the two combined digits.

Amounts to be subtracted are set up on the entering relays in the form of 9's complements and, where the balance is negative, the accumulating relays will receive a setting representing the complement of the balance. The contacts controlled by the relays are so interconnected that tens carry requirements are recognized and proper entries effected from order to order.

For each accumulator order there is provided a series of numeral representing lamps constituting a readout device. Through contacts adjustably set by the accumulating relays in an order, the lamp corresponding to the value standing in the order is illuminated to indicate the true value of the amount set on the relays. A pair of plus and minus sign indicating lamps is also provided to indicate the algebraic sign of the indicated amount.

Before describing the circuits, a brief descrip-

tion will be given of the keyboard construction and of the accumulating relays.

Keyboard

In Fig. 1 is shown a portion of the keyboard and a row of keys designated 1, of which there is one for each of the digits, and a row is provided for each denominational order to be handled by the machine. The keys are suitably mounted for vertical reciprocation in a framework generally designated 2, in which there is a series of horizontally slidable latching bars 3, one for each column of keys. Each key 1 is provided with a locking pin 4 which, when the key is depressed, rocks the related bar 3 toward the left to release any previously latched key. Upon such depression, the bar 3 under the influence of its spring 5 snaps back over the pin 4 of the depressed key. Each of the digit keys 1 is provided with a set or sets of contacts, generally designated *a* in Fig. 1, with one of the blades curved and inclined as indicated at 6 for co-operation with a stud or roller 7 on the key stem 1. The portion 6 acts as a return spring for the key set so that, when released, the pressure of the spring 6 against stud 7 will elevate the key to its normal position.

The several contacts associated with the keys are shown diagrammatically in Fig. 5 where the complete set of keys for one order is shown. Directly beneath each key are the contacts *a*, arranged to convert the digit into a coded equivalent directly or in the form of a 9's complement. The circuits involved will be more specifically pointed out in connection with the description of the circuit diagram.

Accumulating relay

One of the accumulating relays is shown in Fig. 2 where the parts are shown in normal or "unset" position. This relay comprises a magnet generally designated A mounted on the frame 14 to which there is pivoted an armature 8 at the point 9 and a bell crank lever 10 at the point 11. Energization of the magnet A will rock armature 8 counterclockwise against the tension of spring 12. This action will draw lever 13 to the left so that a spring 17 will rock the lever about its pivot 23 on armature 8 to the dotted line position shown in Fig. 2. Pivoted to extension 14a of the frame 14 is a T-shaped lever 15 which is rotatable on the pin 16. The spring 17 is connected between the extremity of lever 15 and a pin 19 on the lever 13 and serves to engage hook 20 of lever 15 to hold it in the position shown in Fig. 2, where a pin 22 bears against the upper end of bell crank 10, holding it in the clockwise position shown, so that its other arm holds the blades of contacts *a*, *b* and *c* in the relative positions indicated.

When magnet A is energized and lever 13 rocked to its dotted line position, the lever 13 is brought into engagement with the upper hook 21 of lever 15 and the spring 17 holds the parts in this position as long as magnet A remains energized. Upon deenergization of the magnet, its spring 12 will return armature 8 and at the same time will rock levers 13 and 15 to the position shown in Fig. 3, in which position the spring 17 will now hold the parts until magnet A is again energized. In this position the pin 22 and a second pin 24 have moved to permit the bell crank lever 10 to rock counterclockwise and enable the contacts associated therewith to take an alternate position as shown.

When magnet A is again energized, the lever 13 will swing back into engagement with the hook 20 and upon deenergization of the magnet the armature 8 will force lever 13 against the hook 20 and the pin 22 will rock the bell crank 10 clockwise back to the position of Fig. 2. In this position it may be noted the pin 24 serves to lock the bell crank 10 against counterclockwise movement.

For each denominational order of the mechanism there are four relays such as shown in Fig. 2, each controlling a plurality of contacts which are specifically designated in the circuit diagram (Fig. 5) where their purpose will be explained. In Fig. 5 the four relay magnets are separately designated as A1, A2, A4 and A8 and the contacts controlled thereby are shown to the right thereof designated by lower case letters.

It is to be borne in mind in following the subsequent explanation that the actual shifting of the contacts occurs upon deenergization of the magnet and that upon energization the shifting levers merely move into position to prepare for the actual shifting of the contacts.

Operating keys

In Fig. 6 are represented plus and minus sign keys designated 25, of which the — key 25 shifts contacts *a* and these are then latched by a bar 3. The + key simply functions to release contacts *a* if they have been previously shifted and latched. When an amount is to be subtracted the — key 25 is depressed and, when an amount is to be added, the + key 25 is depressed, although it is apparent that such latter key need not be operated unless the — key is in its down position.

An operating key 26 and a clearing key 27 are also provided which close contacts *a* thereof only while the keys are held depressed, and which contacts open of their own resiliency when the keys are released.

Circuit diagram

Referring now to Fig. 5, there are represented the devices for one denominational order of the mechanism with the wiring having sets of plug connection sockets designated 28, 29, 30 and 31 by means of which several orders may be coupled through connections generally designated 32 in Fig. 6 to form an accumulator. In the lowest order, connections are made to the contacts of keys 26 and 27 and, in the highest order, connections are made to the contacts of the minus key 25 and to a pair of sign indicating lamps 33.

Current for the device is supplied through negative line 34 to one of the sockets 28 of the units order and through positive line 35 to one of the sockets 29 of the same order.

In the circuit diagram (Fig. 5) are represented the four accumulating relay magnets A1, A2, A4 and A8 for an order, and the contacts controlled by the magnets are designated *a*, *b*, *c*, *d*, *e*, etc. In the tracing of circuits through these contacts they will be designated by the reference character of the magnet followed by the letter of the particular contacts and also followed by the letter L or R to indicate whether the movable blade of the contact is in its left hand or right hand position. Thus, for example, the designation A8bR denotes the *b* contacts of the A8 relay magnet in its right hand position. This system of identification of the contacts is utilized to simplify the application of reference characters to the numerous contacts appearing in the drawings.

For each denominational order there is also provided a set of four relay magnets designated R1, R2, R4 and R8, with each of which is associated a series of contacts designated by lower case letters and which will be similarly identified as, for example, R8aR or R8aL as the case may be. These relay magnets are of the type which shift their contacts upon energization and enable the contacts to return to the normal positions shown upon deenergization.

For each denominational order there is provided a set of digit representing lamps generally designated 36, and for the entire apparatus there are provided the two lamps 33 (Fig. 6) which indicate whether the amount standing in the accumulating relays is negative or positive.

In each order of the accumulator the four magnets A1, A2, A4, and A8 may be considered as having a set or an unset position or condition. These magnets by their condition represent in combinational manner the ten digits. The particular combination for the form illustrated is that of the binary system of notation, and for this reason the magnets are designated with the numerals 1, 2, 4 and 8 to indicate the terms of the binary progression with which the magnets are in correspondence. Thus, the digit 1 is represented on the magnets by the setting of magnet A1, the digit 2 by the magnet A2, the digit 3 by magnets A1 and A2, etc.

Entering an amount additively

To enter an amount, keys 1 are depressed and latched in accordance with the value to be entered. Assuming that the amount 96 is to be entered, the 6 key 1 of the units order and the 9 key 1 of the tens order are depressed and their a contacts are accordingly closed. As a result, the R2 and R4 relay magnets of the units order and the R1 and R8 relay magnets of the tens order will become energized in accordance with the code combinations for the digits 6 and 9, respectively.

The circuits involved are as follows. Referring to Figs. 5 and 6, negative line 34 extends across all orders to the upper contacts a of the - key 25 and continues back through wire 38, so that line 34 and wire 38 are electrically connected. For the units order, current flows from line 34, through wire 39 (Fig. 5), the a contacts of the 6 key 1 lying along the horizontal line designated 2, the 2 wire 40, relay R2, to positive line 35. Concurrently, current flows from wire 38, wire 41, branch wire 42, a contacts of the 6 key in the 4 position, the 4 wire 40, relay R4 to line 35.

In the tens order, the circuit for relay R1 is traceable from wire 38, wire 41, the a contacts of the 9 key in the 1 position, the 1 wire 40 and relay R1 to line 35. The circuit for relay R8 is traceable from wire 38, wire 41, a branch wire 43, the a contacts of the 9 key in the 8 position, the 8 wire 40, relay R8 to line 35.

Inspection of the upper part of Fig. 5 will show that for each of the other digits the R relays will be energized in accordance with the binary combination through either wire 39 or 41.

Entering an amount subtractively

When an amount is to be subtractively entered, the - key 25 (Fig. 6) is depressed and latched prior to operation of keys 1. This results in opening the upper a contacts of key 25 and closing the lower a contacts to electrically connect line 34 with wire 44 which extends back through all the orders. Assuming the same amount 96 is to

be subtractively entered, the circuits for the 6 key in the units order are traceable on Fig. 5 as follows: from line 34, wire 39, a contacts of the 6 key in the 2 position, 2 wire 40, relay R2 to line 35. Concurrently, there is a circuit from negative wire 44, wire 45, a contacts of the 6 key in the 1 position, 1 wire 40, relay R1 to line 35.

For the 9 key in the tens order there will be no circuits completed, since both its contacts are connected to the wire 38 which is now disconnected from line 34. Inspection of Fig. 5 will show that for each of the other digits the R relays will be energized in accordance with the binary combination of the 9's complement of the digit through either wire 39 or 45.

Adding a digit in the units order—without carry

Since the present mechanism is to perform subtractive operations, consideration must be had for the so-called elusive or fugitive one, and in the present case provision is made to control the adding in the units order through the highest, or in the instant example, the thousands order. The circuits are so designed that this control through the highest order is also effected during adding of positive amounts in the novel manner, which will be clearer by taking the specific example of entering a 6 in the units order. Under such assumption the magnets R2 and R4 in the units order are energized under control of the 6 key of the units order as explained. The R1 and R8 magnets of this order and all R magnets in higher orders are deenergized. The A magnets in all orders are in their unset position, that is, their contacts are in the positions shown in Fig. 5.

Closure of the a contacts of key 26 (Fig. 6) connects negative line 34 through wire 46 to a wire 47 extending across all accumulator orders, and under the conditions assumed a circuit can be traced from line 34, contacts of key 26, wire 46, wire 47 (Fig. 5 considered now as the thousands order), a wire 53, contacts A4jR, R4kR, R8hR, A8iR, wire 49, connection to a wire 54 (Fig. 6), connection to wire 55 extending back across all orders to wire 56 which is connected to wire 50 in the units order (see Fig. 5). From wire 50 (considering Fig. 5 as the units order) the circuit continues through a wire 51, the right handmost of six one way current flow devices 52 in the form of rectifiers, contacts R1hR, R2fL, R4gL, A8gR, A4jR, A2eR, CLaD (representing the a contacts of a relay CL in down position), magnet A2, to positive line 35.

A parallel circuit is traceable from wire 50, through wire 51, the fourth rectifier 52 from the left, contacts R1jR, R2dL, R4dL, A8fR, CLbD, magnet A4 to positive line 35. Thus, the magnets A2 and A4 in the units order are energized and when the contacts of operating key 26 reopen, the mechanism associated with these magnets will shift the related contacts to their set positions.

Briefly, it may be stated that when the highest order of the accumulator contains no entry or, as may be seen from inspection, any entry other than 9, the energizing circuit for the units order is directed through the wires 55 and 56 to the wire 50 of the units order. To show that this is so, assume that the thousands order contains an 8, evidenced by the A8 magnet in that order being in its set position. Then the circuit runs from negative wire 47, wire 53, contacts R1jR, A1fR, R2gR, A2gR, A4hR, R4jR, R8gR, A8iL, wire 49, wire 54 (Fig. 6) to wire 55, and thence through the units order wire 50 as before.

It may, therefore, be generally stated that the summation circuit through the lowest or units order is completed through wire 50 and the carry determining set of contacts of the highest or thousands order. Obviously, if subtracting operations were not involved and the highest order chosen were far enough to the left so that no significant entries will be made therein during a succession of additive entries, such highest order will always remain at a 0 setting and the summation circuit for the units order will always follow the path traced from negative wire 34, through the carry determining contacts of the thousands order, to wire 50 in the units order and its non-carry wire 51. From here the circuits will vary according to the digits to be added and will result in setting the A magnets to represent the units digit of the sum of the two digits.

It will be explained later under "Subtraction" that when an amount is subtractively entered (by adding the 9's complement thereof), the sum may change from a negative value represented by a complementary setting of the accumulator, to a positive setting. In such case the highest order will alter its control of the summation circuit for the lowest order to introduce the so-called elusive or fugitive one into such summation to increase it by one unit.

Entering a digit in the units order—with carry

Consider now the addition of an 8 to the 6 already entered. Then, at the time the operating key 26 is depressed the relays will be conditioned as follows:

Amount	Thousands	Hundreds	Tens	Units
6	-----	-----	-----	- A2 A4 -
8	-----	-----	-----	- - - RS

which is to result in

14	-----	-----	A1 -----	- - A4 -

Upon depression of key 26, a circuit is traceable from negative wire 47 (Fig. 5 as units order), wire 53 carry determining contacts A4jL, R4mR, R3jL, A3jR, wire 57, to wire 58 in the tens order in which the circuit extends, through a branch 59 (Fig. 5 as tens order), contacts R1bR, CLdD, magnet A1 to positive line 35. This will cause entry of a unit in the tens order, this unit being the result of a tens carry from the units order, where 6 and 8 are added.

The circuit through the units order magnets is controlled through the thousands order contacts as before with the circuit being traceable from negative wire 47 (thousands order), wire 53, contacts A4jR, R4kR, R3hR, A3iR, wire 49, wire 54, wire 55 (units order), wire 56 to wire 50, wire 51, rectifier 52 farthest to the right, contacts R1hR, R2jR, R4iR, R8eL, A2eL, CLdD, magnet A2 to line 35. As a result, when key 26 is released, the contacts of magnet A2 shift back to their unset position, leaving only magnet A4 set in the units order, and in the tens order the contacts of magnet A1 become set.

Analyzing the conditions thus far considered, it will be observed that in the units order the wire 53 extends to sets of contacts arranged at its left and right which determine whether the sum of the two digits to be added in that order is less than or more than 9. If less than 9, they direct the circuit to so-called non-carry wires 49, 50 as traced for the initial entry of 6 (6+0 being

less than 9). If more than 9, they direct the circuit to so-called carry wires 57, 58 as traced for the entry of 8 (6+8 being more than 9). Stated in another way, for the tens and each higher order the impulse from negative side of line enters through wire 53 and branches through the carry determining contacts to non-carry wire 49 if the sum of the digits to be added in the order is less than 9, and to the carry wire 57 if the sum is more than 9. In the next higher order then, this impulse will continue through wires 51 or 59 if a non-carry or carry is indicated respectively to continue through one part or another of the set of summation contacts to adjust the A relays accordingly. The summation contacts through which the impulse from the non-carry wire 51 passes are interconnected in accordance with the table of addition, and the contacts through which the impulse from the carry wire 59 passes are interconnected in accordance with the table of addition plus a unit, so the ultimate setting of the A relays is one unit higher than the units digit of the sum of the two digits added in an order.

As already explained for the units order, when adding only is being performed, there will be no carry into the units order but the impulse to the non-carry wires 50 and 51 of this order passes through the highest order.

In the special case where the units digit of the sum of two digits to be added in an order is 9 or the order initially stands at 9, an impulse entering such order through carry wires 58, 59 will go through the latter to add a unit in that order and will also branch through the carry determining contacts to the carry wire 57 to the next higher order, to also add a unit therein. This is the so-called carry-on-carry. Inspection of the circuit connections through the set of C contacts (Fig. 5) will disclose that, whenever relays A or R are set to represent 9, or both are set to represent a total of 9, no circuit can be completed through these C contacts from wires 47, 53. When subtracting is performed and a complement stands in the accumulator so that the highest order (thousands) stands at 9 and a positive amount is to be entered, which will change the accumulator setting to a positive quantity, there will be a carry into such highest order from its carry wire 58, through the carry determining contacts (set at 9) to its carry wire 57 (see Fig. 6), and thence through wires 61, 62, 63 to the carry wire 58 in the units order, from which the branch 59 continues the circuit through the summation contacts in the units order to add a unit to the sum of the digits added in that order.

To make the understanding of the circuit connections clearer, Fig. 4 illustrates connections to the negative wire 47 with the sets of carry determining contacts represented as switches C and D, each having three positions "over," "under," and "9." When the sum of the two digits in an order is over 9, switches C and D are in their "over" position, when the sum is less than 9, they are in their "under" position, and when the sum is equal to 9, they are in their "9" position. In Fig. 4 switch arm C represents the set of carry determining contacts designated C in Fig. 5, and indicates that when the sum of two digits in an order is under 9, these contacts form a closed connection from negative wire 53 to the non-carry wire 49 extending to the corresponding wire 50 in the next higher order; that when the sum is over 9, there is no circuit through these contacts; and that when the sum is 9, the contacts connect the

non-carry wire 50 to the non-carry wire 49 and non-carry wire 50 in the higher order. Switch arm D represents the set of carry determining contacts designated D in Fig. 5, and indicates that when the sum of two digits in an order is under 9, they complete no circuit; that when the sum is over 9 they connect the negative wire 53 to the carry wire 57 to send a unit to the next higher order; and that when the sum is 9, they connect the carry wire 58 to such carry wire 57. Thus, the contacts represented by switches C and D provide for all conditions of carry and carry-on-carry between orders, with the special provision of a carry into the units order from the highest order when the latter is to change its setting from 9 to 0.

The circuits take care of a special condition wherein, as the result of the addition of a positive amount added to a complement standing in the accumulator, the result will be 0 in all orders. Thus, for example, if the complement is 9997 and a 2 is added, the resultant setting will be 9999. Under such circumstances all switches C and D will be in their 9 positions and no circuit will be completed to negative source through wire 47. For this reason a set of zero balance contacts designated E in Fig. 5 and represented by switch E in Fig. 4 are provided which, when a 9 condition is set in all orders, will complete a series circuit as clear from Fig. 4, running from negative wire 47, through all switches E to the non-carry wire 49 in the highest order, and thence through wires 54, 55 and 56 to the non-carry wire 50 in the units order to change its setting from 7 to 9.

Considering the previously traced operations again but with respect to Fig. 4, with the A magnets all unset and the R magnets in the units order energized to add 6, switches C and D in all orders will be as shown in Fig. 4 and the circuit from negative wire 47 extends through units wire 53, switch C, wires 49, 50 to the tens non-carry wires 51. Concurrently, a circuit from negative wire 47 extends through thousands wire 53, switch C, wires 49, 54, 55, 56 and 50 to the units non-carry wire 51.

For the second operation where 8 is added to 6, switches C and D in the units order are in their "over" positions and all others are in the "under" positions, and the circuit from negative wire 47 extends through units wire 53, switch D, to carry wires 57, 58 in the tens order. Concurrently, the circuit from negative wire 47 extends through thousands wire 53, switch C, wires 49, 54, 55, 56 and 50 to the units non-carry wire 51.

Considering now the example of 25 added to 14, the circuits involved will be traced in connection with both Figs. 4 and 5. Upon depression of the entering keys, the magnet contacts will be set as follows:

Amount	Thousands	Hundreds	Tens	Units
14	-----	-----	A1 -----	--- A4 ---
25	-----	-----	- R2 ---	R1 - R4 -

which is to result in

39	-----	-----	A1 A2 --	A1 -- A8

In the units order switches C and D will be in their 9 positions and in all other orders they will be in their "under" positions. Upon depression of key 26, a circuit is traceable from nega-

tive wire 47, wire 53, in the thousands order, switch C (representing contacts A4jR, R4kR, R8hR, A8iR, wire 49), wires 54, 55, 56 to non-carry wire 50 in the units order, thence through wire 51, rectifier 52, second from the left, contacts R1dL, A1cR, R2bR, R4bL, A4bL, A2bR, CLcD, magnet A8 to line 35.

A parallel circuit extends from wire 51, rectifier 52, fourth from the left, contacts R1fL, A1dR, R2dR, R4fL, A4eL, CLbD, magnet A4 to line 35.

A third parallel circuit extends from wire 51, contacts R1bL, CLdD, magnet A1 to line 35. When key 26 is released, the contacts of magnet A4 will become unset and the contacts of magnets A1 and A8 will become set.

A still further circuit extends from units wire 50, through switch C (Fig. 4) or in Fig. 5, contacts R1jL, A1fR, R2gR, A2gG, A4iL, R4kL, R8hR, A8iR, non-carry wires 49, 50 to the tens order. In this order the circuit extends through wire 51, rectifier 52, farthest to the right, contacts R1hR, R2fL, R4gR, R8jR, A8hR, CLaD, magnet A2 to line 35. When key 26 is released, the contacts of magnet A2 become set so that the digit 3 is now entered in the tens order and a 9 stands in the units order.

In Fig. 5 the four branch circuit connections extending upwardly from the non-carry wire 51 continue through separate paths to each control 30 one of the magnets A1, A2, A4 or A8, through the contacts of the summation set which are wired in accordance with the table of addition for binary representations. Through these four connections the A magnets in each order will have their settings changed to represent the units digit of the sum of the two digits initially set on the A and R magnets of the order, and the contacts and connections involved may be termed a non-carry adding relay chain.

40 In a like manner the four circuit connections extending upwardly from the carry wire 59 continue through separate paths to each control one of the magnets A1 to A8 to change their settings to represent one unit higher than the units digit 45 of the sum of the two digits initially set on the A and R magnets of the order. In other words, the determining contact chains represented by switches C and D of Fig. 4 select either the non-carry adding chain or the carry adding chain 50 for operation in the next higher order. It is to be particularly noted that, when the R relays have been set to represent the amount to be added, the momentary closure of the contacts of key 26 will concurrently complete all the necessary circuits to adjust the A relays in accordance with the total.

Carry-on-carry example

The circuits involved in an example where the so-called carry-on-carry conditions exist will be traced for a better understanding of the arrangement. Considering the example of 62 added to 39, upon depression of the entering keys the magnet contacts will be set as follows:

Amount	Thousands	Hundreds	Tens	Units
39	-----	-----	A1 A2 --	A1 -- A8
62	-----	-----	- R2R4 --	- R2 --

which is to result in

101	-----	A1 -----	-----	A1 -----

75 Referring to Fig. 4, the switches C and D in

the units order will be in their "over" positions. In the tens order they will be in their 9 positions, and in the higher orders they will be in their "under" positions. When the operating key contacts are closed, a circuit is traceable from negative wire 47, units wire 53, switch D to carry wires 57, 58 (or in Fig. 5 contacts R2iL, A2iR, A4kR, R4mR, R8iR, A8jL, wires 57, 58), tens wire 59, contacts R1bR, CLdD, relay A1 to line 35. Thus relay A1 will become unset.

A parallel circuit extends from tens wire 59, rectifier 52, fifth from the left, contacts R1gR, A1eL, R2eL, R4hL, A2eL, CLdD, magnet A2 (to unset the same), and to line 35. Thus, the tens order will represent 0.

A further parallel circuit extends from the tens wire 58, through switch D (Fig. 4) in the 9 position to carry wires 57, 58 extending to the hundreds order, or in Fig. 5 from tens wire 58, contacts R1kR, A1gL, R2jL, A2jL, A4mR, R4nL, R8jR, A8jR, carry wires 57, 58 to the hundreds order where the circuit continues through wire 59, contacts R1bR, CLdD, magnet A1 to line 35, to thereby enter a 1 in the hundreds order.

For the units order the circuit is traceable in the same manner as previously explained from negative wire 47, the thousands wire 53 (Fig. 4), switch C, and then through wires 49, 54, 55, 56 to the units order non-carry wire 50, from whence it branches through the adding network to energize magnet A8, leaving magnet A1 alone in set condition and there is then set, upon release of the operating key, the sum 101.

Subtraction

As already explained, subtraction is effected by depressing the entering keys in accordance with the amount to be subtracted which includes depressing the 0 keys in orders to the left of the highest significant position, and depressing the - key 25. This results in energizing the R relay magnets in accordance with the 9's complement of the amount to be subtracted and from such point the operation is one of addition. Considering the example of 84 subtracted from 101, upon depression of the entering keys the magnet contacts will be set as follows:

Amount	Thousands	Hundreds	Tens	Units
+ 101				
- 84	R1 --- R8	A1 --- R8	R1 ---	A1 --- R1 - R4 -

which is to result in

+17	----	----	A1 ---	A1A2A4-

The circuits involved in this subtraction may be briefly explained in connection with Fig. 4, wherein the switches C and D for the units and tens positions will be set at "under," the switches C and D for the hundreds order will be set at "over," and the switches for the thousands order will be set at 9. Upon closure of the operating key contacts, current flows from negative wire 47, units wire 53, switch C, non-carry wires 49, 50 to the tens order wherein a single circuit is completed to energize magnet A1 for setting of its contacts.

A parallel circuit runs from wire 47, tens wire 53, switch C, non-carry wires 49, 50 to the hundreds order wherein also a single circuit is completed to energize the magnet A1 for unsetting of its contacts. A further circuit extends from wire 47, through the hundreds wire 53, switch D

(set at "over"), carry wires 57, 58 to the thousands order where the circuit branches through switch D (set at 9) to carry wire 57, a connection 61, wire 62 (see also Fig. 6) connection 63 to the carry wire 58 in the units order, from which it branches through the adding chains to energize magnets A2 and A4 to effect a setting of 7 therein. Thus, through this circuit the so-called fugitive or elusive one is entered in the 10 units order to produce the correct total.

Inspection will thus show that whenever the highest order R magnets are set to represent 9 and the total is to result in a positive amount, the setting of the units order is through its carry 15 wire 58.

Considering now the example of 19 subtracted from 17, upon depression of the entering keys the magnet contacts will be set as follows:

20	Amount	Thousands	Hundreds	Tens	Units
	+17	----	----	A1 ---	A1A2A4-
	-19	R1 --- R8	R1 --- R8	---	---

25 which is to result in

-2	A1 --- A8	A1 --- A8	A1 --- A8	A1A2A4-

This negative result will be set on the A magnets as a 9's complement and with reference to Fig. 4 the switches C and D of the units order will be at "under," the switches C and D of the tens order will be at 9, the switches C and D of the hundreds order will be at 9, and the switches 30 C and D of the thousands order will be at 9. Adding will take place as though the two positive amounts 17 and 9980 were added to obtain 9997 with adding in the units order being through the non-carry wire 50. Such adding circuits will be apparent from the foregoing examples, so the 35 same will not be repeated.

As a further example, consider the subtraction of 590 from 340. Upon depression of the entering 40 keys, the magnet contacts will be set as follows:

30	Amount	Thousands	Hundreds	Tens	Units
	+ 340	----		--- A4 -	----
	- 590	R1 --- R8	A1A2 ---	--- R4 -	R1 --- R8

which is to result in

- 250	A1 --- A8	A1A2A4 -	--- A4 -	A1 --- A8

In the units order switches C and D will be set at 9, in the tens order switches C and D will be set at "under," in the hundreds order switches C and D will be set at "under," and in the thousands order switches C and D will be set at 9. Adding will take place as though the two positive 60 amounts 340 and 9409 were added to obtain 9749. In this example, no carries are required and the summation circuits for each order are traceable 65 in Fig. 4 as follows: For the hundreds order, from negative wire 47, wire 53 in the tens order, switch C (tens) in its "under" position, to non-carry wire 51 of the hundreds order. For the thousands order, from negative wire 47, wire 53 in the hundreds order, switch C (hundreds) in its "under" position, to non-carry wire 51 of the thousands order. For the units order, branches 70 from non-carry wire 51 of the thousands order, switch C (thousands) in its 9 position, wire 49, 54, 55 and 56 to the non-carry wire 51 in the units 75

order. For the tens order, branches from the non-carry wire 51 of the units order, switch C (units) in its 9 position to the non-carry wire 51 of the tens order. Thus, in all orders the non-carry wire 51 conducts the impulse through the summation chain of contacts.

Assuming now a still further example of subtracting 590 from a negative 340 standing in the accumulator as 9659, its 9's complement. Upon depression of the entering keys the magnet contacts will be set as follows:

Amount	Thousands	Hundreds	Tens	Units
-340	A1--A8	-A2A4-- R1-R4--	A1-A4-- R1--R8	A1--A8
+590	-----			-----

which is to result in

+250	-----	-A2--	A1-A4--	-----

In the units order switches C and D will be set at 9, in the tens order switches C and D will be set at "over," in the hundreds order switches C and D will be set at "over," and in the thousands order switches C and D will be set at 9. Adding will take place as though the two positive amounts 9659 and 590 were added to produce 0249, which however requires a fugitive one correction to produce the correct result 0250.

The summation circuits for each order will be as follows: for the hundreds order, from negative wire 47, wire 53 in the tens order, switch D (tens) in its "over" position, to carry wire 59 of the hundreds order. For the thousands order, from negative wire 47, wire 53 in the hundreds order, switch D (hundreds) in its "over" position, to carry wire 59 in the thousands order. For the units position, branches from carry wire 59 of the thousands order, switch D (thousands) in its 9 position, wires 57, 61, 62, 63, 58 to carry wire 59 in the units order to enter the sum of 9 and a fugitive 1 in this order. For the tens order the circuit branches from carry wire 59 of the units order, switch D (units) in its 9 position, to carry wire 59 of the tens order to enter the sum of 5 and 9 and a carried unit in this order.

A special condition arises when an amount is added to a complement standing on the A magnets which reduces the result to 0. For example, assume a 2 to be added to the complement 9997. Then upon depression of the operating keys the magnet contacts will be set as follows:

Amount	Thousands	Hundreds	Tens	Units
-2	A1--A8	A1--A8	A1--A8	A1A2A4-- -R2--
+2	-----			

which is to result in

-0	A1--A8	A1--A8	A1--A8	A1--A8

Inspection of Fig. 4 shows that for this condition all the C and D switches will stand in their 9 positions and consequently there is no connection to the line 47. An additional circuit path is provided which under these circumstances is traceable from the units wire 48 (connected to negative wire 47, Fig. 6), through contacts R1nR (Fig. 5), A1hL, R2kL, R4oR, A4oL, A2kL, wire 65 to wire 48 of the tens order, contacts R1nR, A1hL, R2kR, R4pR, R8kR, A8kL, A4pR, A2kR, wire 65 to wire 48 of the hundreds

order, through which it continues the same as through the tens order, and then through the thousands wire 48 and the same contacts as in the tens and hundreds orders to the thousands wire 65 which in Fig. 6 is connected by a wire 66 to the non-carry wires 54, 55 and 56 to the units non-carry wire 50, through which it goes through the adding chain to energize magnets A2 and A4 to unset the contacts and magnet A8 to set its contacts. When the operating key is released, all the A1 and A8 magnets will have their contacts in a set condition.

The circuit just traced is represented in Fig. 4 where the contact chains between wires 48 and 65 in each order are represented by switches E having an open position and a closed or "9" position.

Sign of total indicating lamps

The lamps 33 (Fig. 6) are controlled by the highest order of the accumulator so that, when this order contains a 9 indicating a negative total, the - lamp 33 is illuminated, and, when it contains any other digit (indicating a positive total), the + lamp 33 is illuminated. For this purpose each order is provided with a switch 67 which is closed in the highest (thousands) order and a circuit is completed as follows: if such highest order is set at a digit other than 9, from negative line 34 (Fig. 5), switch 67, contacts A1tR, to wire 68 which in Fig. 6 connects through a wire 69 to + lamp 33 and positive line 35. With a 9 standing in the thousands order the circuit is from line 34, switch 67, contacts A1tL, A8oL, to wire 70 which in Fig. 6 connects through a wire 71 to - lamp 33 and positive line 35.

The highest order of the accumulator is any order high enough in denomination so that no direct entries are made therein; that is, it is devoted entirely to sign determination and fugitive one control, so that no erroneous entry will result.

Total indicating lamps

Briefly, then, when the total is positive, wires 68 in all orders are connected to negative line 34 and, when the total is negative, wires 70 in all orders are connected to negative line 34. In each order directly above lamps 36 is a circuit network through which the positive value of the total is displayed under control of contacts of the A magnets. A pair of examples will serve to illustrate. Assuming a positive digit of 7 to be standing in an order (represented by a setting of the contacts of magnets A1, A2 and A4), then a circuit will be traceable from negative line 34, wire 68, contacts A2mL, A4rL, A1kL, 7 lamp 36 to positive line 35. Assuming a negative digit of 7 to be standing in an order (represented by a setting of the contacts of magnet A2), then a circuit will be traceable from negative line 34, wire 70, contacts A2nL, A4tR, A1mR, 7 lamp 36 to positive line 35. Similar circuits are readily traceable for each of the other digits.

Clearing the accumulator

When it is desired to clear the accumulator, key 27 (Fig. 6) is depressed to close its contacts and as a result relay magnets CL (Fig. 5) become energized through a circuit from line 34, contacts of key 27, wire 72 extending across all the accumulators, the magnets CL in parallel, to line 35. In each order the magnet CL shifts its contacts a, b, c and d from the down position shown to their up position and any A magnets, whose contacts are in set position, will have a

pair of *a* contacts closed to direct an impulse to the magnet to shift the contacts to unset position. Specifically, assuming magnet A2 (Fig. 5) to be set with its contacts A2a shifted to the left, then when contacts CLa shift, a circuit is traceable from line 34, wire 73, contacts A2aL, CLaU, magnet A2 to line 35. Upon release of key 27 the shift to unset position takes place and the lamps display +0000.

There is thus disclosed an improved relay accumulator in which, after a relay setting of an amount to be entered and its sign have been effected, a single momentary impulse will effect the algebraic summation. It is to be noted that the entry key settings remain latched until a new setting is effected or all 0 keys are operated. This enables repeated entry of the same amount simply by the repeated operation of key 26 so that multiplication may readily be performed in accordance with the method of repeated addition.

Modification

Fig. 7 shows a modified arrangement of the adding circuit connections wherein the adding-with-carry connections are entirely separated from the adding-without-carry connections. For this arrangement the A magnets are provided with two windings as indicated with one set of windings controlled through connections and relay contacts extending from the non-carry wire 51 and the second set extending from the carry wire 59. For comparison, the same reference characters are used for corresponding contacts in Fig. 5 and inspection will show that the circuit connections extending through all the contacts down to the R1 contacts are the same. The R1 contacts are divided into two separate sets, one under the group designated non-carry and the other under the group designated carry with the two groups being the same above these contacts. In the right hand, or additional control group, the same reference characters as in the first are employed with a prime and, when comparison is made with Fig. 5, it will be observed that the circuit arrangement of the latter figure is in effect the two groups of contacts of Fig. 7 merged into one with one way current flow rectifiers 52 employed to prevent back circuits, and by this means the carry and non-carry adding connections traverse common paths for the greater extent of their paths between wires 51 or 59 and the A magnets.

The circuit of Fig. 5 may be still further simplified by the omission of the circuit connections and contacts from contacts A2k down through R1n, if it is determined in advance that a negative 0 will not occur in the handling of accounting problems, since as explained these contacts are provided to take care of the special case where the sum in all orders is 9.

While there have been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination, in a relay accumulator, a group of contact sets, one set for each denominational order of the accumulator, each set be-

ing adjusted to represent a digit of the amount in the accumulator, a plurality of magnets for each order for adjusting said contacts, a second group of contact sets, one set for each denominational order of the accumulator, each set being adjusted to represent a digit of an amount to be entered into the accumulator, adjusting means therefor, a first set of circuit connections, for each order, interconnecting a first part of the contacts and said magnets of the related order in accordance with the table of addition for the two digits, a second set of circuit connections, for each order, interconnecting a second part of the contacts and said magnets of the related order in accordance with the table of addition for the two digits plus a carry digit, a third set of circuit connections, for each order, interconnecting a third part of the contacts in accordance with the table of addition for the two digits, a fourth set of circuit connections, for each order, interconnecting a fourth part of the contacts in accordance with the table of addition for the two digits, the first and second sets of connections of each order being connected in series with the third and fourth sets of connections, respectively, of the next lower order, the first and second sets of connections of the lowest order being connected in series with the third and fourth sets of connections, respectively, of the highest order, a pair of current source lines, said magnets being connected to one of said lines, a pair of operating contacts connected to the other of said lines, and effective when the sum in each order of the two digits set therein is under 9, for completing parallel circuits extending serially through the first sets of connections of each order and the third sets of connections in series therewith to the other of said source lines to cause the magnets to adjust their contacts to represent the sum of the two amounts.

2. In combination, in a relay accumulator, a group of contact sets, one set for each denominational order of the accumulator, each set being adjusted to represent a digit of the amount in the accumulator, a plurality of magnets for each order for adjusting said contacts, a second group of contact sets, one set for each denominational order of the accumulator, each set being adjusted to represent a digit of an amount to be entered into the accumulator, adjusting means therefor, a first set of circuit connections, for each order, interconnecting a first part of the contacts and said magnets of the related order in accordance with the table of addition for the two digits, a second set of circuit connections, for each order, interconnecting a second part of the contacts and said magnets of the related order in accordance with the table of addition for the two digits plus a carry digit, a third set of circuit connections, for each order, interconnecting a third part of the contacts in accordance with the table of addition for the two digits, a fourth set of circuit connections, for each order, interconnecting a fourth part of the contacts in accordance with the table of addition for the two digits, the first and second sets of connections of each order being connected in series with the third and fourth sets of connections, respectively, of the next lower order, the first and second sets of connections of the lowest order being connected in series with the third and fourth sets of connections, respectively, of the highest order, a pair of current source lines,

said magnets being connected to one of said lines, a pair of operating contacts connected to the other of said lines, and effective when the sum in each order of the two digits set therein is over 9, for completing parallel circuits extending serially through the second sets of connections of each order and the fourth sets of connections in series therewith to the other of said source lines to cause the magnets to adjust their contacts to represent the sum of the two amounts.

3. In combination, in a relay accumulator, a group of contact sets, one set for each denominational order of the accumulator, each set being adjusted to represent a digit of the amount in the accumulator, a plurality of magnets for each order for adjusting said contacts, a second group of contact sets, one set for each denominational order of the accumulator, each set being adjusted to represent a digit of an amount to be entered into the accumulator, adjusting means therefor, a first set of circuit connections, for each order, interconnecting a first part of the contacts and said magnets of the related order in accordance with the table of addition for the two digits, a second set of circuit connections, for each order, interconnecting a second part of the contacts and said magnets of the related order in accordance with the table of addition for the two digits plus a carry digit, a third set of circuit connections, for each order, interconnecting a third part of the contacts in accordance with the table of addition for the two digits, a fourth set of circuit connections, for each order, interconnecting a fourth part of the contacts in accordance with the table of addition for the two digits, the first and second sets of connections of each order being connected in series with the third and fourth sets of connections, respectively, of the next lower order, the first and second sets of connections of the lowest order being connected in series with the third and fourth sets of connections, respectively, of the highest order, a pair of current source lines, said magnets being connected to one of said lines, a pair of operating contacts connected to the other of said lines, and effective when the sum in a higher order is under 9, the sum in the next lower order is 9, and the sum in the second lower order is over 9, for completing a circuit extending serially through the second set of connections of said higher order, the fourth set of connections of the next lower order and the fourth set of connections of the second lower order to the other of said source lines, and effective for concurrently completing a circuit extending serially through the second set of connections of said next lower order and the fourth set of connections of the second lower order to the other of said source lines.

4. The invention set forth in claim 1 in which a fifth set of circuit connections is provided for each order, said sets of connections being con-

nected in series and arranged to complete a circuit, when the sum of the two digits in each order is 9, connecting the first set of connections of the lowest order to the other of said source lines.

5. In a relay accumulator, having contacts settable to represent an amount therein, entering contacts in each order settable to represent an amount or the 9's complement of an amount to be entered, in combination with magnets operable to adjust the first named contacts to represent any amount, a first group of circuit connections including part of said contacts and the magnets arranged and normally effective to cause the magnets to adjust the first named contacts in accordance with the sum of the two amounts set on the two sets of contacts, a second group of circuit connections including part of said contacts and the magnets arranged to cause the magnets to adjust the first named contacts in accordance with the sum of the two amounts +1, and means controlled by a part of the contacts of each order, when the sum of the digits set on the related contacts is greater than 9, for rendering the first group of connections in the next higher order ineffective and rendering the second group of connections effective, the means controlled by said part of the contacts of the highest order being effective when the sum of the digits therein is greater than 9 for rendering the first group of connections related to the lowest order ineffective and rendering the second group thereof effective.
6. An electrical relay accumulator comprising, for each denominational order, a plurality of accumulating relays settable to represent a digit, a plurality of entering relays settable to represent a digit to be added, a first set of contacts adjusted by the accumulating relays, a first set of contacts adjusted by the entering relays, said sets of contacts being interconnected in accordance with the table of addition, to effect a setting of the accumulating relays to represent therein the units digit of the sum of the two digits to be added, a second set of contacts adjusted by the accumulating relays, a second set of contacts adjusted by the entering relays, said second sets of contacts being interconnected in accordance with the table of addition to effect a setting of the accumulating relays to represent one digit more than the units digit of the sum of the two digits to be added, means for selectively completing a circuit through either set of contacts, a third set of contacts adjusted by the accumulating relays, a third set of contacts adjusted by the entering relays, means jointly controlled by the said third sets of contacts of each order for determining whether the sum of the digits in an order is greater or less than 9, said determining means acting concurrently for all orders to render the selective completing means of all higher orders concurrently effective to complete a circuit through the first or second sets of contacts of all such higher orders, and means controlled by the determining means of the highest order for rendering the selective completing means of the lowest order effective to complete a circuit through the first or second named sets of contacts.

HANS P. LUHN.
